UNITED STATES PATENT OFFICE.

JOHN HAYES, JR., OF AMSTERDAM, AND JOSEPH BERGER, JR., OF UTICA, NEW YORK, ASSIGNEES TO UNION SPECIAL SEWING MACHINE COMPANY, OF CHICAGO, ILLINOIS, A CORPORATION OF ILLINOIS.

SEWING AND TRIMMING MACHINE.

No. 902,532.

Specification of Letters Patent.

Patented Oct. 27, 1908.

Application filed March 5, 1904. Serial No. 196,772.

To all whom it may concern:

Be it known that we, JOHN HAYES, JR., and JOSEPH BERGER, Jr., citizens of the United States, residing, respectively, at 5 Amsterdam, in the county of Montgomery, and Utica, Oneida county, State of New York, have invented certain new and useful Improvements in Sewing and Trimming Machines, of which the following is a description, reference being had to the accompanying drawing and to the letters and figures of reference marked thereon.

Our invention relates to sewing machines, and especially to a sewing machine for use 15 in the manufacture of underwear, for carrying out the operation of necking undershirts or finishing the tails of undershirts.

The object of the invention, primarily, is to provide a novel arrangement of trimming 20 mechanism, combined with a twin needle machine, whereby in one operation, two layers of fabric may be fed to the machine, a stationary cutting member on the cloth plate may penetrate between the layers, and a 25 movable member coöperating therewith, may work from below and sever the edge of the lower layer, the stitch-forming mechanism uniting the two layers, and at the same time, the under thread carrying looper will lay 30 its thread across the cut edge of the lower fabric and bind its raw edge.

So far as the details of the trimming mechanism itself are concerned, they may be applicable to other types of machines, but 35 the invention as a whole is especially useful at the present time in the necking of undershirts, where the fabric is doubled and fed to the machine, the point of the stationary cutting member passing into the bend of the 40 goods, the lower layer being severed and the two layers being united and the raw edge covered by the looper thread of the stitch forming mechanism. It will be understood, however, that the invention may be applied 45 to other uses.

The invention consists in the matters hereinafter described and referred to in the appended claims.

The invention is illustrated in the accompanying drawings, in which—

Figure 1 is a front elevation of a sewing machine embodying the invention; Fig. 2 is a perspective view of the cloth plate, feed dog, and trimming device, showing the fab-

ric partly broken away; Fig. 3 is a similar view of the throat plate, illustrating also the two needles of the stitch-forming mechanism; Fig. 4 is a sectional side view of a portion of a sewing machine embodying our invention; Fig. 5 is a perspective view of the feed dog with the cutting member attached thereto; Fig. 6 is a sectional view of the feed dog and movable cutter; Fig. 6^a is a similar view, showing the adjustment of the movable blade; and Fig. 7 is a view of the work done on the machine. Fig. 8 is a plan view of the throat plate, feed dog and cutter, showing the relations of the various elements.

In these drawings, the machine as a whole 70 is of the well known Union Special twin needle type of machine, and embodies as its stitch-forming mechanism two needles *n*, *n*, and an under thread-carrying looper *l*, the thread of the latter concatenating with the 75 loops of needle thread on the under side of the cloth plate, and carrying its thread back and forth across the line of feed.

A represents the throat plate, which is of usual construction for a machine of this 80 character, except that its forward portion is slotted as at *a*, to receive the shank *b* of the upper or stationary cutter *C*, which is secured to the throat plate by the screw *B*. At its opposite end the cutter *C* is slotted 85 at *a*³ to fit over a projection *a'* on the throat plate. It has a forwardly projecting sharp point *s*, against which the layers of fabric are pressed and which penetrates between the two, as shown in Fig. 2. The notched portion *c*, acts as a guide for the lower layer of fabric, and as a partial support for it in the cutting operation of the lower knife, against the under side *c* of the upper member. The vertical wall of the upper member acts after the cutting to separate the trimmed from the untrimmed portion of the lower layer of fabric, and the upper member as a whole acts as a separator between the layers of fabric. The lower cutting blade *K* is attached to and moves with, the feed dog, being attached thereto, as shown in Fig. 6, by the screw *f*, but preferably is adjustable vertically, as shown in Fig. 6^a, for the purpose of taking up wear 100 due to the dulling and consequent re-sharpening of the tool.

In Figs. 7 and 8, and 2, the operation of

the machine as to the work done thereon, is illustrated.

In the operation of necking of undershirts, the doubled fabric F, G, is placed in the machine, with the point s of the upper cutter penetrating the fold, as the goods are drawn along by the feed, the lower fabric to the right is severed, the upper layer passes over the upper blade, C, and the parts then reach the stitch-forming mechanism, when two rows of stitches are passed through the fabrics, one some distance within the raw edge of the severed fabric, and the other just outside, or at the edge, the looper thread securing the needle threads and lying across the raw edge of the severed fabric.

Having thus, described our invention, what we claim as new, and desire to secure by Letters Patent, is:—

1. In a sewing machine, and in combination with the stitching mechanism and feed dog thereof, a knife fixed in and located above the throat plate of the machine in advance of the stitching mechanism, and comprising a member projecting horizontally over the plane of the cloth plate, substantially in the line of feed, and a movable knife carried by said feed dog and co-acting with said fixed knife; substantially as described.
2. In a sewing machine and in combination with the stitching mechanism thereof, a fixed cutter, comprising a member projecting forward over the plane of the throat plate, a feed dog, and a movable cutter supported by said feed dog and co-acting with said fixed cutter.
3. In a sewing machine and in combination with the stitching mechanism thereof, a fixed cutter comprising a member projecting forward over the plane of the throat plate, a feed dog, a pin or screw projecting therefrom, and a movable cutter carried by said pin or screw.
4. In a sewing machine, and in combination with the overstitching mechanism thereof, a trimming device comprising an upper stationary member having its forward end adapted to enter between two superposed layers of fabric and a lower member co-operating therewith to sever the lower layer of fabric, said trimming device being arranged in advance of the stitch forming mechanism and the stationary member being substantially in line with one edge of the overstitching, whereby only one of said cut edges is stitched.
5. In a sewing machine and in combination with the stitching mechanism thereof, comprising a pair of needles, a trimming device comprising an upper stationary member having its forward end adapted to enter between two superposed layers of fabric, and a lower member co-operating therewith

to sever the lower layer of fabric, said trimming device being arranged in advance of the stitch forming mechanism, and the said stationary member being in the line of feed and in front of and in line with one of the needles.

6. In a sewing machine and in combination with the stitching mechanism thereof, a throat plate having a pair of openings for the needles, and cutting mechanism comprising a knife detachably supported by said throat plate and being located substantially in front of and in line with one of said needle openings in the line of feed.

7. In a sewing machine, the combination of an overstitching mechanism, means for feeding a plurality of thicknesses of material, a cutting mechanism including an upper stationary member adapted to penetrate between two layers of fabric, and a movable co-operating lower member carried by the feeding mechanism and adjustable thereon, to sever the lower layer of fabric, the said stitching mechanism being located behind the cutting mechanism and arranged to sew one of the cut edges to the uncut fabric by covering the cut edge, said cutting mechanism being arranged in the line of feed and substantially in line with the edge of the over stitch substantially as described.

8. In a sewing machine, the combination with stitch-forming mechanism including a plurality of needles arranged to pass parallel rows of loops through the fabric to be sewed and a thread carrying device co-operating with the needles to make a cross stitch, of a trimming mechanism including an upper stationary member secured to the throat-plate and extending above the same and adapted to enter between two superposed layers of fabric to be sewed, and a lower movable member co-operating therewith to sever the lower fabric, the said stitching mechanism being located behind the trimming mechanism and arranged to sew one of the cut edges to the uncut fabric by covering the cut edge, said cutting mechanism being arranged in the line of feed and substantially in line with the edge of the over stitch substantially as described.

9. In a sewing machine, the combination with stitch-forming mechanism including a plurality of needles arranged to pass parallel rows of loops through the fabric to be sewed and a thread carrying device co-operating with the needles to make a cross stitch, of a trimming mechanism including an upper stationary member secured to the throat-plate and extending above the same, having a sharp point projecting toward the front of the machine and adapted to enter between two superposed layers of fabric to be sewed, and a lower movable member co-operating therewith to sever the lower fabric, the said stitching mechanism being located

behind the trimming mechanism and arranged to sew one of the cut edges to the uncut fabric by covering the cut edge, said cutting mechanism being arranged in the line of feed and substantially in line with the edge of the over stitch substantially as described.

10. In a sewing machine, the combination with stitch-forming mechanism including a plurality of needles arranged to pass parallel rows of loops through the fabric to be sewed and a thread carrying device coöperating with the needles to make a cross stitch, of a trimming mechanism including an upper stationary member secured to the throat-plate and extending above the same and adapted to enter between two superposed layers of fabric to be sewed, and a lower movable member coöperating therewith to sever the lower fabric, the said stitching mechanism being located behind the trimming mechanism and arranged to sew one of the cut edges to the uncut fabric by covering the cut edge, and means for adjusting the lower member, said cutting mechanism being arranged in the line of feed and substantially in line with the edge of the over stitch substantially as described.

11. In a sewing machine having a throat

plate, cutting mechanism including a knife 30 detachably supported at one end on the throat plate, and at its opposite end provided with a recess engaging a projection on the throat plate; substantially as described.

12. In a sewing machine having a throat plate, provided with a recess at its forward portion, and a projection in rear thereof, and a knife resting in said forward recess, and at its opposite end having a recess engaging 40 said projection; substantially as described.

13. A trimming mechanism including upper and lower knives, the former having a fabric-penetrating point and having a guiding slot, the walls of which serve as a 45 guide for the lower layer of fabric and as a partial support for it in the cutting operation of the lower knife against the under side of the upper member; substantially as described.

In testimony whereof we affix our signatures, in presence of two witnesses.
